CLAIM

The ornamental design for a weight for a sippy cup straw, as shown and described.

DESCRIPTION

FIG. 1 is a perspective view of my weight for a sippy cup straw;

FIG. 2 is a front side elevational view;

FIG. 3 is a rear side elevational view;

FIG. 4 is a left side elevational view of FIG. 2;

FIG. 5 is a right side elevational view of FIG. 2;

FIG. 6 is a top plan view of FIG. 4; and,

FIG. 7 is a bottom plan view of the FIG. 4.

The broken lines depict environment that form no part of the claimed design.
